UNITED STATES PATENT OFFICE.

BERNARD DREYFUSS, OF NEW YORK, N. Y.

DESIGN FOR AN EMBROIDERY-PATTERN.

Specification forming part of Design No. **11,275**, dated July 1, 1879; application filed April 21, 1879.
[Term of patent 3½ years.]

To all whom it may concern:

Be it known that I, BERNARD DREYFUSS, of the city, county, and State of New York, have invented and produced a new and original Design for an Embroidery-Pattern, of which the following is a full, clear, and exact description, reference being had to the accompanying drawing, making part of this specification.

A represents an embroidery-pattern, having the outline of a leaf, with a margin, *a*, having perforations *b* formed in it at regular intervals. The entire body-work of the pattern-leaf is also perforated, as at *c*. These perfor-

ations are designed to receive worsted-work for ornamentation, also as a means for uniting several of the leaf-patterns together, so as to make card-baskets or other similar things.

What I claim as my invention is—

The design for an embroidery-pattern, consisting of the leaf-shaped pattern, having the perforated margin and perforated body, substantially as described, and shown in the accompanying illustration.

BERNARD DREYFUSS.
